CLAIM

The ornamental design for heating equipment, as shown and described.

DESCRIPTION

FIG. 1 is a front perspective view of the heating equipment showing my new design;

FIG. 2 is a front view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.

The broken lines in FIG. 3 form no part of the claimed design.
